Application November 18, 1948, Serial No. 60,703
In Great Britain November 19, 1947

9 Claims. (Cl. 260—428)

1

This invention relates to a novel method of treating fatty oils containing vitamin A to remove flavor-imparting material from such oils and, if desired, to increase the concentration of the vitamin A therein.

Oils containing vitamin A (within which term is to be included in this specification vitamin A esters, vitamin A alcohol, or any provitamin A) are used for the vitaminization of foodstuffs, such as margarine and for this purpose it is desirable that the oil should possess no objectionable flavors.

Certain processes for removing objectionable flavors from oils are already well known. Some of these processes only remove part of the compounds which give the objectionable flavors. Moreover, in certain of these processes new substances giving objectionable flavors may be formed. Other processes, when applied to oils containing vitamin A, have the disadvantage of resulting in undesirable losses of the vitamin or an undesirable change in the vitamin. In certain processes the vitamin A esters are completely converted into the vitamin A alcohol, which is more unstable.

The chromatographic treatment of vitamin containing oils has also been proposed for various purposes, but no practicable process for removing objectionable flavors from such oils is believed to have been devised so far.

It is an object of the present invention to provide a process for the complete removal of objectionable flavors from vitamin A containing oils which is simple in operation and by means of which satisfactory yields of recovered vitamin may be obtained.

Another object of the invention is to provide a method for simultaneously removing completely the objectionable flavors from vitamin A containing oils and increasing the concentration of vitamin A therein.

The present invention uses a chromatographic method and employs for this purpose a column of activated alumina to be defined and described in more detail hereinafter through which the oil, in solution in a non-polar saturated hydrocarbon or a mixture of such hydrocarbons is passed. It has been found that all the undesirable and objectionable flavors are retained on the alumina, while the resulting bland-tasting oil comprising the major portion of the original oil and containing most of the vitamin A in a chemically unaltered form passes through.

For chromatographic processes various forms of activated alumina are known, as well as various methods of preparing the material. For the treatment of materials containing relatively unstable compounds such as vitamin A, a highly active material is undesirable as, apart from other considerations, it tends to bring about destruction

2

of the vitamin, and to introduce other undesirable changes in the oil. The various methods proposed for de-activating highly active aluminas, for example by exposure to a humid atmosphere or by the addition of water, have the disadvantage that the degree of deactivation is difficult to control, and the alumina, after use, can be reactivated only by difficult treatment and cannot readily be brought back to the original activity in a simple manner.

Alumina is known to exist in a number of distinct forms. One of these is the gamma form, which has already been described in the literature, for example in the article by Blitz et al., 15 "Zeitschrift für anorganische Chemie," volume 186, page 373. It has been found that by using a column of crystalline gamma anhydrous alumina in the chromatographic treatment of oils containing vitamin A in solution in a non-polar hydrocarbon solvent, the fishy and other undesirable flavors may be removed while the oil, containing the vitamins in solution, passes through the column.

Such an alumina may be prepared by heating a 25 crystalline gamma alumina tri-hydrate to a temperature and for a length of time sufficient to drive off the combined water, but insufficient to convert the material to the inert crystalline alpha form. The complete change from the tri-hydrate to the gamma anhydrous state takes place 30 above 500° C. The activity of the material, although exhibiting the same immediate and abrupt change, does not remain static with continued heating, but decreases, and the rate of decrease and the limiting value which is obtained 35 depend upon the temperature.

In the accompanying drawing there are shown curves giving the relation between time of activation and activity at various temperatures.

40 The activity of the alumina may be measured by its absorptive capacity for a dye. One method for making such measurements is as follows:

A solution of waxoline blue in dry, freshly distilled petrol ether is prepared and its optical 45 density at 650 mu for a 1 cm. depth of solution is adjusted to 2.00 just prior to the test. 0.2 g. of freshly heated alumina is added to 50 c. c. of dye solution in a 150 c. c. stoppered flask, dispersed well and allowed to stand for 5 minutes. The 50 dye solution is then decanted and the alumina washed with 2 lots of 5 c. c. petroleum ether. The adsorbed dye is removed with successive lots (4 c. c. + 4 c. c. + 2 c. c.) of absolute alcohol and filtered through a small sintered glass crucible. 55 The filtrate is transferred to a 10 c. c. graduated flask, adjusted to this volume and the strength of solution determined. From this the weight of dye in milligrams adsorbed by 1 g. of alumina is calculated, and this is used as a measure of the 60 activity.

It is found that for removing the fishy flavors from oils containing vitamin A, a material having an adsorptive capacity for waxoline blue of between 4.5 and 7.0 mgm. per g. of alumina, measured as described in the preceding paragraph, is suitable. The material should be substantially free from adsorbed water, in distinction to the material deactivated by water referred to previously.

According to the present invention therefore, there is provided a process for the treatment of oils containing vitamin A (as hereinbefore defined) which comprises passing the oil in solution in a non-polar saturated hydrocarbon or mixture of such hydrocarbons, through a column of anhydrous activated gamma alumina free from adsorbed water, whereby objectionable flavors are removed from the oil, and separating the resulting bland-tasting oil from the solvent. Preferably the column of alumina is washed with further quantities of solvent until as much as possible of the oil and vitamin are recovered without the objectionable flavored substances held on the column also being washed out.

The use of the above described form of alumina is particularly advantageous when the process for the treatment of the oils is carried out on a large scale. Owing to the fact that the alumina reaches a steady state of activity on heating, this state may be arrived at again by heating to the same temperature. This fact is made use of to economic advantage in the large scale application of the invention. A column of alumina, after being used to treat the oil, may be revivified first by washing with a hydrocarbon solvent containing say 10% alcohol. This alcohol displaces the adsorbed substances of the alumina. The column is then heated (for example by means of steam which is passed through a surrounding jacket), and the alcohol is driven off by passing warm air through the column. When all the alcohol is removed, the column is ready for the treatment of a further batch of oil. After a number of such treatments the material is found to become less efficient and the alumina is removed. It can then be reactivated simply by heating to the same temperature to which it was originally activated, whereupon it is ready for a further cycle of treatment, being revivified as described above after each treatment.

Any non-polar saturated liquid hydrocarbon or mixture of such hydrocarbons may be used as solvent for dissolving the oil treatment in accordance with the present invention. In the examples that follow petroleum ether (B. P. 40° to 60° C.) is described as a solvent, but other non-polar hydrocarbon solvents such as benzine (B. P. 75°-95° C.) or cyclohexane may be used.

While it is to be understood that the invention is not to be limited by any theory advanced herein, it is believed that the non-polarity of the solvent, or the lesser polarity thereof as compared with the fishy factor in the oil, prevents displacement of the fishy factor, which is one of the least strongly adsorbed zones of all the various non-triglyceride substances removed by the column.

It is found, in general, that the most satisfactory concentration of the oil in the solution in hydrocarbon lies between 15% and 30% weight of oil/volume of solution (grams/cc.). However, concentrations of as low as 10% or less and as high as 40% or more have been found useful.

The ratio of weight of alumina is the column

to the weight of oil treated before the alumina is revivified has a considerable effect upon the results obtained. When the ratio is low, i. e., of the order of less than 1:1, the removal of objectionable flavors generally tends to be incomplete but the recovery of vitamin A tends to approach 100%. When the ratio is somewhat higher, i. e., of the order of 2:1 or 3:1, the removal of objectionable flavors is substantially complete and the concentration of the vitamin in the recovered oil is about the same as in the initial oil. When the ratio is high, i. e., of the order of 10:1 or 20:1 or higher, the removal of the objectionable flavors is complete and the concentration of vitamin in the recovered oil is raised remarkably with surprisingly little loss of vitamin, since it is found that the alumina retains a portion of the oil while the vitamin passes through with the unadsorbed oil.

When the method is carried out primarily for the purpose of removing the objectionable flavors without increasing the concentration of the vitamin, the ratio of weight of alumina in the column to the weight of oil treated in a given run is therefore preferably maintained at about 3:1, although lower ratios as low as about 1:1 may be used.

When the method is carried out primarily for the purpose of increasing the concentration of the vitamin in the oil, and incidentally to achieve complete removal of the objectionable flavors, the ratio of weight of alumina in the column to the weight of oil treated in a given run is preferably maintained at above 3:1.

The following examples are illustrative of the several ways in which the present invention may be practiced.

Example 1

50 grams of a soda-refined shark liver oil containing 100,000 I. U. per gram of vitamin A ester were made into a 25% weight/volume (grams/cc.) solution in petroleum ether (B. P. 40° C.-60° C.). This solution was passed through a column having an internal diameter of 1½" (internal diameter) and containing 150 grams of alumina in an activated anhydrous gamma form. The column was washed with 300 cc. of the same petroleum ether and the final washings were almost completely free from oil. The recovered oil, after removal of the solvent, was free from objectionable flavors. 47.6 grams of oil were recovered having a potency of 100,000 I. U. per gram, corresponding to a recovery of 95.2% of the vitamin A.

Example 2

21 grams of a crude dogfish liver oil containing 17,000 I. U. per gram of vitamin A ester were made into a 25% weight/volume solution in benzine (B. P. 75° C.-95° C.). This solution was passed through a column having an internal diameter of one inch and containing 63 grams of alumina as described in Example 1. The column was washed with 157 cc. of fresh benzine. 20.1 grams of oil were recovered and were free from objectionable flavors. The potency of the recovered oil was 16,500 I. U. per gram, corresponding to a recovery of 92.6% of the vitamin A.

Example 3

50 grams of a soda-refined whale liver oil having a vitamin A potency of 12,600 I. U. per gram, of which about 70% was in the form of the alcohol, were made into a 25% weight/volume solution in petroleum ether (B. P. 40° C.-60° C.). This solution was passed through a column hav-

ing an internal diameter of $1\frac{1}{8}$ " and containing 150 grams of alumina as described in Example 1. The column was washed with 350 cc. of petroleum ether. 48.6 grams of oil, free from objectionable flavors, were recovered. The potency of the recovered oil was 11,700 I. U. per gram, corresponding to a recovery of 90.1% of the vitamin A.

Example 4

50 grams of a soda-refined palm oil containing 474 micrograms of carotene per gram were made into a 25% weight/volume solution in benzine (B. P. 75° C.-95° C.). The solution was passed through a column having an internal diameter of one inch and containing 100 grams of alumina as described in Example 1. The column was washed with 350 cc. of fresh benzine. 46.5 grams of oil, free from objectionable flavors, were recovered. The recovered oil contained 454 micrograms of carotene per gram, corresponding to a recovery of 89.7%.

Example 5

50 grams of a soda-refined shark liver oil containing 99,000 I. U. per gram of vitamin A ester were made into a 25% weight/volume solution in petroleum ether (B. P. 40° C.-60° C.). This solution was passed through a column having an internal diameter of $1\frac{1}{8}$ " and containing 150 grams of alumina in an activated crystalline anhydrous form. The column was washed with further quantities of petroleum ether until the washings were almost completely free from oil (about 350 cc.). 44.6 grams of oil were recovered. After removal of the solvent, the recovered oil had a potency of 98,500 I. U. per gram, corresponding to a recovery of 88.9% of vitamin A.

Example 6

35 grams of a crude dogfish liver oil having a vitamin A potency of 1600 I. U. per gram were made into a 25% weight/volume solution in petroleum ether (B. P. 40-60° C.). This solution was passed through a column having an internal diameter of $1\frac{1}{4}$ " and containing 400 grams of alumina as described in Example 1. The column was washed with 1400 cc. of petroleum ether. 4.47 grams of oil, free from objectionable flavors, were recovered. The potency of the recovered oil was 8800 I. U. per gram, corresponding to a recovery of 82.0% of the vitamin A.

Example 7

10 grams of a crude liver oil having a vitamin A potency of 160,000 I. U. per gram were made into 25% weight/volume solution in petroleum ether (B. P. 40-60° C.). This solution was passed through a column having an internal diameter of $1\frac{1}{8}$ " and containing 200 grams of alumina as described in Example 1. The column was washed with 600 cc. of petroleum ether. 1.35 grams of oil, free from objectionable flavors, were recovered. The potency of the recovered oil was 1,056,000 I. U. per gram, corresponding to a recovery of 89% of the vitamin A.

It should be understood that the above description and examples are merely illustrative of the invention and that any changes obvious to those skilled in the art may be made without departing from the scope of the invention as defined by the following claims.

I claim:

1. A process for removing undesirable flavor-imparting materials from an oil containing vita-

min A without reducing appreciably the vitamin A content of the oil which comprises dissolving said oil in a non-polar saturated hydrocarbon solvent and passing the resultant solution through anhydrous gamma alumina.

2. A process as defined in claim 1 wherein the anhydrous gamma alumina is formed by heating crystalline gamma alumina trihydrate to a temperature above 500° C. for a length of time sufficient to drive off the combined water but insufficient to convert the material to the inert crystalline alpha form and wherein the anhydrous gamma alumina has a uniform adsorptive capacity for waxoline blue dye of between 4.5 and 7.0 mgm. per gram of alumina.

3. A process as defined in claim 1 wherein the ratio of weight of alumina to the weight of treated oil is of the order of about 1:1 to about 3:1 to substantially remove the flavor-imparting material from said oil, but insufficient to increase the concentration of vitamin in the oil.

4. A process as defined in claim 1 wherein the ratio of weight of alumina to the weight of treated oil is at least 1:1.

5. A process as defined in claim 1 wherein the ratio of weight of alumina to the weight of treated oil is of the order of about 10:1 to about 20:1 to increase the concentration of the vitamin in the oil.

6. A process as defined in claim 1 wherein the concentration of oil in the hydrocarbon solution is within the range of 10 to 40 parts by weight of oil in 100 parts by volume of solution.

7. A method which comprises alternately passing a solution of vitamin A-containing oil in a non-polar saturated hydrocarbon solvent through a column of anhydrous gamma alumina and revivifying the alumina in situ by washing the column with a mixture of non-polar saturated hydrocarbon solvent and alcohol and heating the alumina until the alcohol is removed therefrom.

8. A method which comprises alternately passing a solution of a vitamin A-containing oil in a non-polar saturated hydrocarbon solvent through a column of anhydrous gamma alumina and reactivating the alumina by heating it to a temperature above 500° C.

9. A process as defined in claim 1 wherein the non-polar saturated hydrocarbon solvent is selected from the group consisting of petroleum ether, benzine and cyclohexane.
